ILLUMINATING DEVICE FOR HOUSE NUMBERS

Herman Lou Millspaugh, Seattle, Wash.

Application September 30, 1940, Serial No. 359,039

1 Claim. (Cl. 240—73)

This invention relates to a device for the illumination of house numbers and, more especially, to a device for this purpose characterized in that the electrical current for illumination is derived from the door-bell circuit of the house. Objectively, the invention aims to provide a device of the character described which may be easily installed and which, over extended periods of usage, maintains efficient illumination with practically negligible bulb burn-outs. For such infrequent burn-outs as may occur, it is a further and particular object to provide an assembly of parts permitting ready access to the lamp for replacement purposes. Other objects and advantages, with the foregoing, will appear in the course of the following description and claim, the invention consisting in the novel construction and in the adaptation and combination of parts illustrated in the accompanying drawing and hereinafter described and claimed.

In said drawing:

Figure 1 is an underside plan view of an illuminating device constructed in accordance with the preferred embodiment of the present invention, the view representing the device as attached to a wall shown in section.

Fig. 2 is a transverse vertical section on line 2—2 of Fig. 1; and

Fig. 3 is a longitudinal vertical section on line 3—3 of Fig. 2.

According to the present invention I provide a plate represented by the numeral 5 desirably produced to a semi-circular plan configuration and having on the inner face a web 6 spaced from but concentric with the arcuate perimeter and arranged to act as a bearing foot with respect to the outer wall of a house on which the device is to be mounted. This plate is or may be of an insulating material such as hard rubber, Bakelite, or the like, and on the front face is fitted with a lamp socket 7, and at each side of the latter is pierced by holes accommodating nails 8 or other securing medium for fixing the plate in a suitable position above the house numbers of the wall. The said socket is designed to receive a 6-8 volt electric lamp 10 and embodies wire leads 11—12 which are arranged to be conventionally attached to opposite terminals of a door-bell circuit (not shown). As a salient feature of my electric circuit, it should be here stated that one of my two leads is nichrome to function as a resistance in maintaining an electric load on the lamp somewhat below the listed capacity thereof. I find that 35-gauge wire supplied in a 24" length enables the user to accommodate the lamp to the electric output of any of the door-bell transformers now in use, the full length of the nichrome wire producing a resistance sufficient

to compensate for an eighteen volt door-bell circuit as conventionally employed with chime bells while a measured shortening of the wire correspondingly reduces the resistance in accordance with the requirements of six and twelve volt circuits.

As a directrix for the light rays I employ a hood 13. For ready detachability with respect to the plate 5, said hood is open at its inner end and about such opening is formed with an in-turned flange which by a marginal correspondence with the perimeter of the web 6 permits the flange to be hooked over the rim of the plate. The hood is painted or otherwise suitably treated on the underside for reflection of light.

It is believed to be apparent that I have devised a structure applicable either to six, twelve, or eighteen volt transformer output by the instrumentality simply of governing the length of one of the two wire leads, developing thereby a resistance operative to reduce the load on the electric lamp below peak capacity and consequently prolonging lamp life. The ease with which the mounting plate 5 is fixed to the wall, and the ready detachability of the hood, are features which augment the operating utility. It is to be expected that minor departures from the disclosed embodiment will readily occur to those versed in the art, and visualizing these changes it is my intention that the hereto annexed claim be given a scope in its interpretation commensurate with the state of the art.

What I claim is:

In a device for the illumination of house numbers: the combination of a mounting plate formed on its back face with an integral web projecting rearwardly in spaced parallel relation to the perimeter of the plate; means for attaching the plate against the wall of the house to have the same lie above the number which is to be illuminated and with the web bearing directly against the wall to describe a peripheral channel about the plate defined at the outside by the back face of the plate and at the inside by said wall of the house; a lamp socket supported on said plate; and a member arranged to fit over the plate to provide a hood for a lamp received in said socket, said hood-forming member being provided about its seating edge with an in-turned flange formed to a thickness permitting the same to be freely lodged in and removed from said peripheral channel, the inner perimeter of said web describing a chamber to the rear of the plate which is open at the bottom to accommodate wires carried from the socket through the back wall of the plate to the lamp-energizing source of current.

H. LOU MILLSPAUGH.
